UNITED STATES PATENT OFFICE.

JOHN W. BROWN, OF NEWARK, NEW JERSEY, ASSIGNOR TO FERDINAND C. BRAND-HURST AND JOHN W. BROWN, COPARTNERS, TRADING UNDER THE NAME AND STYLE OF CRYSTAL CUT GLASS COMPANY, OF NEWARK, NEW JERSEY.

DESIGN FOR A COMBINED MIRROR AND FLOWER HOLDER.

Application filed February 16, 1926. Serial No. 16,541. Term of patent 14 years.

To all whom it may concern:

Be it known that I, JOHN W. BROWN, a citizen of the United States, residing at 217 South 10th Street, Newark, county of Essex, State of New Jersey, have invented a new, original, and ornamental Design for Combined Mirror and Flower Holder, of which the following is a specification, reference being had to the accompanying drawing, forming part thereof.

Fig. 1 is a front elevational view of a combined mirror and flower holder, embodying my new design.

Fig. 2 is a top plan view of Fig. 1.

I claim:

The ornamental design for a combined mirror and flower holder, as shown.

JOHN W. BROWN.
